CUSHION

Carl Hugo Gerlofson and Theodore J. Nelson,
Chicago, Ill.

Application July 1, 1931, Serial No. 548,133

6 Claims. (Cl. 155—179)

This invention relates to a cushioning member. In one form it may be embodied in a cushion for use on a seat, as a seat cushion, or for use as a back cushion, or for any other cushioning use so as to cushion the person of an individual. Its most common use will be as a seat cushion and as a back cushion, although it may be used in any association in which it is desired to provide a cushioning member and to provide a surface ventilating member.

One object of the invention is, therefore, to provide a combined cushioning and surface ventilating member wherein the surface which is supported by the cushion is also ventilated. Another object is to provide in a cushion means for permitting free circulation of air from the exterior thereto and therethrough. Another object is to provide in a ventilating cushion member, means for causing the passage of air through the cushion and into and out of the cushion along its edges and along its top and bottom.

Other objects will appear from time to time in the specification and claims.

The invention is illustrated more or less diagrammatically in the accompanying drawing, wherein:

Figure 1 is a plan view;

Figure 2 is a fragmentary showing of an inverted plan view on an enlarged scale;

Figure 3 is a vertical cross section taken at line 3—3 of Figure 2, on an enlarged scale; and

Figure 4 is a vertical cross section taken at line 4—4 of Figure 2, on an enlarged scale.

Like parts are designated by like characters throughout the specification and drawing.

The cushion, which is made of yielding material and preferably of rubber or sponge rubber, is formed generally of a sheet-like member or body A which may be provided with perforations A¹. Along its edge the member A may be provided with a downwardly facing and downwardly depending flange or enlargement A². This enlargement may be of any suitable shape but is conveniently so shaped as to provide a curved or rounded edge A³ for the cushion. A fabric or other covering A⁴ may be fastened upon the cushion.

Positioned upon the under surface of the cushion member A and preferably formed integrally with it is a plurality of columns or stud-like supporting members B. These are preferably tapered along their sides as at B¹ and at their bottom ends may be cup-shaped as at B² to provide suction engaging cups. For some purposes it is advantageous to reinforce the column mem-

bers B. This may be done by forming a web B³ between two or more of them and engaging the member A, as indicated generally in Figure 2 and in detail in Figure 3. The members may be otherwise reinforced by a vane or flange-like portion B⁴ which may engage one of the members B and, being inclined downwardly, engage the cushion sheet-like member A. The reinforcing or strengthening or stiffening effect which occurs by the use of the members B³ or B⁴ may be accomplished at any point in the cushion. Any of the members B may be reinforced in this manner. Ordinarily, it is not necessary to do so except adjacent the edges of the cushion and it is in this manner that the reinforcing is shown in the figures herewith.

It will be realized that whereas our invention is herewith shown and described as a practical operation device, nevertheless many changes might be made in the size, shape, number and disposition of parts without departing from the spirit of the invention and we wish, therefore, that our showing be taken as in a sense diagrammatic. In particular, the cushion device shown may be of any shape and might be made without the fabric covering, and the support members B might be of any suitable shape. They might or might not be joined together by the members B³ or by the members B⁴ and for some purposes the cup-like dépressions B² might be omitted.

The use and operation of our invention is as follows:

The cushioning member is made as shown preferably of sponge rubber, that is to say, of a rubber in which a quantity of voids, air spaces or bubbles is formed throughout the body of the rubber, and will ordinarily be positioned upon or against a surface so that the supporting column-like members B have their ends upon this surface. Thus a cushion may be positioned upon a chair seat or against the back of a chair. It will be noticed that the members B are higher or extend downward farther than the flange A². Thus this flange is out of contact with the surface upon which the cushion is supported and so the entire edge of the cushion is open to the air, since the flange A² does not make contact with the support upon which or against which the cushion rests.

Since the entire edge of the cushion is open to the air and since the interior body of the cushion is interrupted only by the column-like members, air may circulate freely to and from the interior of the cushion, entering along the edge

and leaving at the edge. Since perforations are also provided throughout the sheet-like member A, air may move in or out through these perforations. Thus complete circulation of air is possible into or out of the cushion through its sides or edges, top or bottom.

Not only is the cushion ventilated so that it provides means for the circulation of air into or through or from it, but because of its construction and because of the material of which it is made, it provides what is in effect a pumping action so that air is positively drawn into the cushion and positively forced from it. If we assume the cushion to be placed upon a seat and if we assume that someone is sitting on the cushion, as the individual moves or shifts his position a varying weight will be applied to different portions of the cushion. When, for example, the person sits on one side of the cushion, that side will be depressed more than the other side. Thus air is forced from that portion of the cushion. When the weight is then shifted, the portion which has been depressed is no longer depressed and because of the elasticity of the material, it expands, tending to draw air into that portion of the cushion. As the cushion moves, this process takes place more or less constantly and as the weight of the user is shifted about on the cushion the air is positively driven from one portion of the cushion and positively driven into another portion of the cushion and thus what is in reality a pumping action is set up within the cushion to circulate air in the cushion, to draw air into and to force air out of it.

Where in the specification and claims we have referred to parts of the cushion as being downwardly depending, this language is used not in a limiting sense but merely as describing the particular form shown in the figures. The cushion there shown is shown as resting upon a seat in which its upper surface occupies a more or less horizontal position and the supporting plugs or columns extend downwardly from the upper surface. If the cushion were used in any other position, as for example against the back of a chair, the surface of the member A would occupy a more or less vertical position and the supporting plugs or columns B would extend more or less horizontally from it. It is to be understood, therefore, that in the specification and claims, where the members have been referred to as projecting downwardly, this language is not used in a limiting sense and is not to be understood as meaning that the cushion must always be used in a more or less horizontal position, with its plug-like members B pointing downwardly.

We claim:

1. In combination in a cushion, a sheet-like

60

upper member provided with perforations, and a plurality of supporting projections formed on the under surface of said sheet-like member, said supporting projections provided with concave depressions in their free ends, the sheet-like member having a downwardly depending thickened edge, the supports projecting downwardly beyond the thickened edge.

2. In combination in a cushion, a sheet-like upper member having its edges beveled and provided with perforations, and a plurality of supporting projections formed on the under surface of said cushion member, projecting in the same direction as the beveled edge of said member, said supports provided with concave depressions in their outer ends, the sheet-like upper member being thickened about its beveled edge said supports projecting downwardly beyond the edge of the cushion.

3. In combination in a cushion, an upper member provided with perforations, and a plurality of supporting projections formed on the under surface of said cushion member, the free ends of said projections defining a supporting plane for the cushion, some of said supports joined to each other by web members, the upper member being thickened about its edge and terminating above the plane defined by said projections.

4. In combination in a cushion, a sheet-like upper member provided with perforations, and a plurality of supporting projections formed on the under surface of said sheet-like member, said supporting projections provided with concave depressions in their free ends, the sheet-like member having a downwardly depending thickened edge raised above the surface upon which the cushion rests, and fabric covering of a material different from the cushion, fastened on its upper surface and co-extensive with that surface.

5. In combination in a cushion, formed of sponge rubber, an upper member provided with perforations and a plurality of supporting projections, the upper member having a downwardly depending edge, the projections extending downwardly beyond said edge said edge being held above the surface upon which the cushion rests, to provide an edge open for air circulation.

6. In combination in a cushion, an upper member, and a plurality of supporting projections, the upper member being thickened about its edges, the projections extending downwardly beyond the edge of the upper member with the free ends of said projections defining a supporting plane spaced from said edge whereby to provide for free circulation of air from the periphery of the cushion into the body thereof, between said projections.
